[57] **CLAIM**

The ornamental design for spur eyelet fastener with uniform circular base for securing ring binder mechanism, as shown and described.

DESCRIPTION

FIG. 1 is a perspective view of a spur eyelet fastener with uniform circular base for securing ring binder mechanism showing my new design, the ring binding structure and the binder cover depicted by means of broken lines have been shown for illustrative purposes only and form no part of the claimed design;

FIG. 2 is a second perspective view;

FIG. 3 is a top plan view;

FIG. 4 is a bottom plan view;

FIG. 5 is a side elevational view;

FIG. 6 is a perspective view of a second embodiment of my design of FIG. 1;

FIG. 7 is a top plan view of the second embodiment;

FIG. 8 is a bottom plan view of the second embodiment; and,

FIG. 9 is a side elevational view of the second embodiment.
